UNITED STATES PATENT OFFICE.

JOHN F. STEVENS AND JACOB G. DAVIS, OF OTTUMWA, IOWA.

CATTLE-STANCHION.

1,232,117.

Specification of Letters Patent. Patented July 3, 1917.

Application filed February 16, 1917. Serial No. 148,950.

To all whom it may concern:

Be it known that we, JOHN F. STEVENS and JACOB G. DAVIS, citizens of the United States, residing at Ottumwa, in the county 5 of Wapello and State of Iowa, have invented certain new and useful Improvements in Cattle-Stanchions, of which the following is a specification.

This invention relates to certain new and 10 useful improvements in cattle stanchions and it has for its primary aim to provide a novel and simple construction in which the cattle may be conveniently locked and released.

15 Further, the invention resides in a yieldably mounted stanchion embodying an improved locking means for the yoke parts thereof, and also in the provision of means whereby the opening of the stanchion may 20 be adjusted to vary the size for the particular animal.

The invention further resides in the improvements, features of construction, and arrangements and combinations of parts 25 hereinafter described and succinctly claimed, reference being had to the accompanying drawing wherein—

Figure 1 is a front elevation of our improved stanchion;

30 Fig. 2 is an irregular section on line 2—2 of Fig. 1;

Fig. 3 is a vertical section through Fig. 1 on line 3—3; and

Fig. 4 is a detailed section of the yoke locking means, said view being taken on line 4—4 of Fig. 2.

Referring more in detail to the accompanying drawing, the numeral 1 designates upper and lower stall frame members to 40 which the stanchion is attached, the latter comprising a fixed yoke part 2 which has its lower end curved and pivotally connected to the similarly shaped end of the movable yoke part 3 by pin 4, each yoke part being 45 respectively connected to the lower frame member 1 by a spring 5, as shown in Fig. 1.

The upper end portion of the fixed yoke part is fixed in the bend of a U-shaped, horizontally disposed bar 6 between the legs of 50 which is guided the upper end of the movable yoke part, the outward limit of swing

of the latter being defined by the stop block 7 that is held in position between the legs by a bolt 8. This bolt passes through registering openings 9 in the legs, a series of such 55 openings being provided so as to afford the block a plurality of adjustments by selectively engaging the bolt in the bar openings, and provide a variable sized opening between the yoke parts. 60

A coiled spring 10 connects the yoke bar 6 with the upper frame member 1, said spring being stronger than the springs 5 since the former suspends the yoke and constitutes the sole support therefor. It is thus obvious 65 that the yoke is yieldably and resiliently mounted, the spring 5 that connects the movable yoke part 3 to the lower frame member also serving to open the yoke by pulling the movable yoke part outwardly against the 70 block 7 when said part is unlocked.

As a safe guard against the cattle lunging forwardly or exerting undue tension on the springs, normally slack chains 11 and 12 are provided, the upper chain connecting 75 the bar 6 to the superposed frame member 1 while the lower chain 12 is anchored to the lower frame member and attached to the pivot pin 4 so as to be centrally secured to the lower side of the yoke. 80

The movable yoke part is provided with a slot 13 through which extends a catch 14 that is pivoted to said part, as at 15, and has its inner end of latch design, said latch end being constantly urged upwardly by a 85 coiled spring 16 which is connected to the opposite end of the catch and is anchored to the part 3, as is clearly seen in Fig. 4. The latch end is formed with a cam face 17 that, when the movable part is closed, engages the keeper 18 to permit of the latch part passing said keeper whereby the spring 16 will effect a proper interlocking of said parts. The keeper is rotatably disposed between the legs of the yoke bar 6 on a shaft 90 19 which carries on a projecting end a fixed lever 20. This lever is urged in one direction by a coiled spring 21 the extent of swing being determined by a stop 22, formed by inturning the lower end of said lever, 100 engaging the under side of said bar 6. The keeper is provided with a kicker part 23

which, when the lever is pulled against the action of the spring 21, will rotate with said keeper and engage the cam face 17 in pushing the catch from engaging relation with the keeper.

5 Mounted on the inner end of the yoke bar is a pulley housing 24 in which is journaled a double pulley 25. A pair of cables or ropes pass under the double pulley and over a 10 guide pulley 26 to a convenient point, the rope 27 being connected by an eye to the movable yoke part and the rope 28 to the lever 20.

In practice, with an animal locked in the 15 stanchion, the parts will be related as depicted in Fig. 1. To release the animal, the rope 28 is pulled to rotate the kicker part 23 against the catch for disengaging the latter from the keeper when the spring 5 will pull the movable yoke part outwardly against the 20 stop block 7. To close the stanchion, it is only necessary to pull on rope 27 which draws the movable part 3 toward the fixed yoke part 2 and the latch into engagement 25 with the keeper by the coöperation of spring 16.

It will be noted that the operation is exceedingly simple and may be performed from a distant point, the construction is durable and embodies but few parts, and the mounting is such as to be inoffensive and non-injurious to the cattle.

The foregoing detailed description has been given for clearness of understanding 35 only, and with no intention of limiting the device to the specific disclosure, it being understood that minor changes as may fall within the scope of the claims may be resorted to to render the structure practical.

40 What is claimed as new is: —

1. In a stanchion, upper and lower frame supporting members, a yoke comprising pivotally connected yoke parts, a yoke bar carried by one part for guiding the other part, 45 means yieldably suspending the yoke from the upper frame member, and individual springs connecting the yoke parts to the lower frame member, said springs being connected to the yoke parts on opposite sides of the pivotal connection.

50 2. In a stanchion, upper and lower frame supporting members, a yoke comprising a fixed and a movable yoke part pivotally connected at their lower ends, a yoke bar carried by the fixed yoke part for guiding the movable yoke part in its movement, a spring connecting the bar to the upper frame member for suspending the yoke, a pair of spring members connecting the lower portion of the yoke, to the underlying lower frame member, one for each yoke part, a chain connecting the bar to the upper frame member for limiting the yieldability of the adjacent spring, and a chain connecting the pivotal

connection of the yoke parts to the lower 65 frame member.

3. In a stanchion, upper and lower frame supporting members, a yoke comprising a fixed and a movable yoke part pivotally connected at their lower ends, a yoke bar carried by the fixed yoke part for guiding the movable yoke part in its movement, a spring connecting the bar to the upper frame member for suspending the yoke, a pair of spring members connecting the lower portion of the yoke to the underlying lower frame member, 70 one for each yoke part, a chain connecting the bar to the upper frame member for limiting the yieldability of the adjacent spring, a chain connecting the pivotal connection 75 of the yoke parts to the lower frame member, a latch carried by the movable yoke part, and a keeper carried by the yoke bar for engagement by the keeper and comprising a kicker part adapted to engage the 80 latch and release the same from its keeper.

4. In a stanchion, a yoke comprising a fixed yoke part, a movable yoke part pivoted to the lower end thereof, a yoke bar having the fixed part secured in its bend and the 90 movable part guided thereby, upper and lower frame supporting members, a spring secured to the bar for suspending the yoke from the upper frame member, a spring secured to the lower part of the fixed yoke 95 part for holding it yieldingly to the lower frame member, and a spring secured to the movable part for connecting the same to the lower frame member and opening the movable part from the fixed part.

100 5. In a stanchion, a yoke comprising pivotally connected yoke parts, a U-shaped bar having the parts positioned between its legs, one fixedly, a latch carried by the other part, and a keeper rotatably arranged between the 105 legs of the U-bar for engagement by the latch, said keeper having a kicker part adapted to engage with the latch when the keeper is rotated to disengage said latch from its keeper.

110 6. In a stanchion, a pair of pivotally connected yoke parts, a yoke bar fixed adjacent the free end of one part and guidingly related to the other part, a latch on the latter, a keeper on the bar with which the latch is 115 adapted to engage, a kicker member carried by the keeper for engaging with and disengaging the latch from the said keeper when the latter is rotated, a lever for rotating the keeper, and means for opening the yoke parts when the latch is disengaged from the keeper.

120 7. In a stanchion, a pair of pivotally connected yoke parts, a yoke bar fixed at one end to the upper end of one part and having its opposite end slidably and guidingly related to the other yoke part, a latch carried by the latter, a rotatable keeper on the

bar with which the latch engages, a kicker member operable by the keeper for disengaging the latch therefrom, a lever for rotating the keeper, a double pulley on the 5 first end of the yoke bar, and a pair of ropes taking over the pulleys, one rope being connected to the movable yoke part and the

other rope having connection with the lever, the latter rope opening the stanchion and the former rope closing the latter. 10

In testimony whereof we affix our signatures.

JOHN F. STEVENS.
JACOB G. DAVIS.
